UNITED STATES PATENT OFFICE.

DUNCAN A. McCONNELL, OF MONTCLAIR, NEW JERSEY, ASSIGNOR TO KLAXON COMPANY, A CORPORATION OF DELAWARE.

MECHANICAL HORN.

1,378,124.

Specification of Letters Patent. Patented May 17, 1921.

Application filed January 30, 1919. Serial No. 273,953.

To all whom it may concern:

Be it known that I, DUNCAN A. McCONNELL, a citizen of the United States, and resident of Montclair, in the county of Essex and State of New Jersey, have invented certain new and useful Improvements in Mechanical Horns, of which the following is a specification.

My present invention relates to horns of the above type, in which a rotor, preferably having cam projections formed on one face, is used to vibrate the diaphragm and particularly to those in which the rotor must have a predetermined relatively high speed in order to produce the proper rate of vibration of the diaphragm which is found in practice to be most effective in producing a warning signal. The invention includes a special form and arrangement of multiplying gear, which particularly adapts the instrument for obtaining the required high speed of the rotor under conditions where only a slowly rotating source of power is available, as for instance, where the horn is hand operated and particularly where a hand crank is employed.

The desirable speed for rotation of the rotor and the speeds conveniently obtainable by means of a hand crank are described in prior patent to Hutchison No. 1,169,721, granted January 25th, 1916, and need not be here repeated.

Considered with reference to said patent, my invention includes improvements in the form and arrangement of the multiplying gear and rotor with respect to each other and with respect to the diaphragm, whereby a cheaper, stronger and more compact instrument is obtained and the use of beveled gears is dispensed with. The above advantages are combined with a simple, more effective, better protected method of oiling the parts.

The nature and object of my inventions will be more fully understood from the following detailed description in connection with the accompanying drawing, in which—

Figure 1 is a vertical central section of the device;

Fig. 2 is a rear elevation of the same.

Referring to said drawings, the diaphragm 1, wearpiece 2, horn or projector 3, front casing 4, and clamps 5, 6, may be of any known or desired construction.

The supporting means may be the same as that shown in the prior patent to Hutchison, above cited, and may comprise the pedestal 7, provided with screw holes 8 for attachment to a suitable support, its upper portion 9 having vertical swivel connection 60 with the shank 10, which is preferably integral with the rear casing of the horn. The latter may be held in any desired position of rotary adjustment by means of the screw 11, engaging groove 12. Any other desired means of support may be employed.

The hand crank 13 is mounted on the drive shaft 14, to which it is locked by a suitable means such as the pin 15. The shaft 14 is perpendicular to the diaphragm 70 and slightly above the center thereof. This makes the plane of rotation of the hand crank parallel with the diaphragm and raises its orbit of movement, thereby giving greater clearance for the hand when the crank is in its lowermost position and also permitting the crank arm 13 to be made longer for a given minimum permissible clearance for the hand.

The drive shaft 14 is journaled in the casing 16, which is thickened, so as to provide an inner boss 18 and an outer boss 17. This gives a long bearing for the shaft, so that possibility of wear is prevented, even though the instrument may be subjected to rough usage for a long time.

On the inner end of the shaft 14 and offset from the inner wall of the casing 16 by means of the boss 18, is the large gear wheel 19. The gear 19 is securely held in place 90 preferably by expanding and riveting over the outer end 21 of the reduced portion 20 of shaft 14, thereby clamping the gear against the annular shoulder 22.

The gear 19 meshes with the pinion 23 95 which is rigidly connected with the rotor 24 and drives the same at the proper rate, which is predetermined by properly selecting the number of teeth on the pinion 23 with reference to the number of teeth on the 100 driving gear 19. For reasons to be explained presently, the axis of the pinion and rotor is parallel with and preferably directly below the axis of the drive shaft 14.

The preferred means for rotatably mounting the pinion and rotor is a stationary stud-shaft, preferably comprising an enlarged outer end 26 of size sufficient to give

ample peripheral bearing surfaces in the wall of the case. The latter is thickened as at 27 to give ample length for such bearing surface. The part of the stud-shaft 5 projecting within the case is reduced, as at 28. On this stationary shaft is rotatably mounted the rigidly connected pinion 23 and rotor 24. The rigid connection of the latter parts is preferably accomplished by 10 reducing and extending the hub of the pinion to form a tubular hub 29 on which the rotor 24 is secured preferably by riveting over the end of the hub as at 29, thereby permanently and effectively clamping the 15 rotor to the pinion. The thus unified rotor and pinion are held in position on the said shaft by means of lock-nuts 30, 30, which are screwed down tight upon a still further reduced extension 31. These units bear 20 upon the shoulder 32 of the shaft and do not clamp or bind the rotary sleeve mounted thereon.

The above construction and arrangement of parts make possible a unique, effective 25 and well protected system of oiling for the drive shaft 14, gear 19, pinion 23 and the cam teeth on rotor 24. The oil is applied through a vertical passage 32, a removable screw plug 33 being used for this purpose, 30 though a removable oil cup of ordinary construction could be employed if desired. The oil flowing downward through passage 32, flows freely in the annular groove 34, in shaft 14. Thence it finds its way in both 35 directions, outward toward the crank end and inward toward the gear 19. Here it lubricates the bearing surface of gear 19 on boss 18, leaks outward, along the gear to the teeth thereof and oils the contacts between the 40 gear teeth of 19 and pinion 23. The surplus oil in 34 has a free drainage downward through the vertical passage 35, into the annular space 36, formed by turning off a portion of the screw threaded periphery of stud 45 26. Oil collecting in the space 36 finds its way through the slotted passage 37 to the exterior of the stud-shaft where it serves to lubricate the inner bearing surface of the pinion. Any oil leaking out between the 50 sleeve end 29 and the lock-nut 30 finds its way to the periphery of the pinion and lubricates the cams, which contact with the wear-piece 2. Surplus oil leaking out from any of the above noted places finds its way into 55 the recess or 'catch' basin 38. If the oil is permitted to accumulate at this point to a slight depth, it will bathe the lowermost portion of the periphery of the rotor and the latter acting as a centrifugal spreader will 60 throw oil upon and thereby lubricate all the movable parts within the casing.

The delicate adjustment of the face cams on the rotor with reference to the wearpiece on the diaphragm, which it is now well understood is necessary for best operation of 65

devices of this type, may be accomplished by simply rotating the stud-shaft, the screw threads 26 operating to retract or advance the rotor, according to which way the said shaft is screwed. When the desired position 70 of adjustment is secured, it may be rendered permanent by locking the shaft in that position by means of the lock-nut 39.

The structural strength of the whole casting and particularly the rigidity of the 75 bosses 17 and 27 with respect to each other, are greatly increased by the integral rib 40 which connects said bosses.

From the above it will be evident that I 80 have succeeded in redesigning, reorganizing and recombining the same number of parts shown in the above mentioned Hutchison patent so as to produce results equal to or better than those obtained by the structure of said patent and at the same time gain 85 many important advantages. For instance, the depth of the casing or body of the horn is greatly decreased, my present structure requiring only that the depth of the case be equal to the thickness of the rotor plus the 90 width of the pinion plus the required amplitude of adjustment of the rotor shaft to and from the diaphragm. The latter factor, the adjustment, is only a very small fraction of an inch, and the other factors, the 95 thickness of the rotor and the width of the pinion, may be very materially less than those shown in the drawing. Another feature is the simplicity and ease of effecting adjustment of the rotor from the outside of 100 the case combined with absolute solidity of support and rigidity of locking of the adjustment.

While I have shown and described a preferred embodiment of my invention with 105 great particularity, it will be understood that various changes, modifications, omissions or substitutions of parts may be made without departing from the spirit of my invention.

I claim:

1. In a horn of the class described, rear and front casings and a diaphragm clamped between them, in combination with means for vibrating the diaphragm, said means including a sleeve with a rotor, and driving pinion thereon, a stationary stud shaft projecting endwise toward the diaphragm from the rear wall of the casing on the inwardly projecting portion of which said rotor and 115 pinion are rotatably mounted, the rear portion of said stud shaft extending through the rear wall of the casing and having screw connection therewith, accessible from the exterior of the casing for endwise adjustment 120 of the rotor to and from the diaphragm, a rotatable driving shaft extending through the rear wall of the casing with its axis parallel to said stud shaft, a large gear mounted on the inner end of said driving 125 shaft, and a gear 130

shaft and engaging said pinion, and a hand crank located outside the casing on said drive shaft.

2. In a horn of the class described, rear and front casings and a diaphragm clamped between them, in combination with means for vibrating the diaphragm, said means including a rotor, a driving pinion therefor, a stationary stud shaft projecting endwise toward the diaphragm from the rear wall of the casing on the projecting portion of which said rotor and pinion are rotatably mounted, the rear portion of said stud extending through the rear wall of the casing and having screw connection therewith, accessible from the exterior of the casing for endwise adjustment of the rotor to and from the diaphragm, a rotatable driving shaft extending through the rear wall of the casing 20 with its axis parallel to said stud shaft, a large gear mounted on the inner end of said driving shaft and engaging said pinion.

3. In a horn of the class described, rear and front casings and, clamped between them, a diaphragm having a suitable wear-piece, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said drive shaft and engaging said pinion, said drive shaft being located above the level of the diaphragm wear-piece and said rotor shaft below and midway between said wear-piece and the bottom of the casing so that the lower portion of its periphery rotates adjacent the lowermost clamped portion of the diaphragm, said parts being formed with an oiling system comprising a downwardly extending passage in the casing leading to the drive shaft intermediate its ends, a passage around the periphery of said drive shaft, a downwardly extending passage leading from the latter to the rotor shaft, a passage around the periphery of the latter.

4. In a horn of the class described, rear and front casings and, clamped between them, a diaphragm having a suitable wear-piece, said rear casing consisting of a casting having its rear wall approximately parallel with and of approximately the same diameter as the unclamped portion of the diaphragm, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said stud shaft, a large gear mounted on the inner end of said driving shaft and engaging said pinion, said rear wall of the casing being thickened adjacent the drive shaft and the rotor shaft to afford long bearing surfaces therefor.

5. In a horn of the class described, rear and front casings and, clamped between them, a diaphragm having a suitable wear-piece, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said drive shaft and engaging said pinion.

said pinion, said drive and rotor shafts having their axes in the same vertical plane with the wear-piece, the drive shaft being above the level of the wear-piece and the rotor shaft below said level.

6. In a horn of the class described, rear and front casings and, clamped between them, a diaphragm having a suitable wear-piece, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said drive shaft and engaging said pinion, said drive shaft being located above the level of the diaphragm wear-piece and said rotor shaft below and midway between said wear-piece and the bottom of the casing so that the lower portion of its periphery rotates adjacent the lowermost clamped portion of the diaphragm, said parts being formed with an oiling system comprising a downwardly extending passage in the casing leading to the drive shaft intermediate its ends, a passage around the periphery of said drive shaft, a downwardly extending passage leading from the latter to the rotor shaft, a passage around the periphery of the latter.

7. In a horn of the class described, rear and front casings and, clamped between them, a diaphragm having a suitable wear-piece, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said stud shaft, a large gear mounted on the inner end of said driving shaft and engaging said pinion, said rear wall of the casing being thickened adjacent the drive shaft and the rotor shaft to afford long bearing surfaces therefor.

8. In a horn of the class described, rear and front casings and, clamped between them, a diaphragm having a suitable wear-piece, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said drive shaft and engaging said pinion.

- on the inner end of which said rotor and pinion are rotatably mounted, said stud extending through the rear wall of the casing and having screw connection therewith, accessible from the exterior of the casing for endwise adjustment of the rotor to and from the diaphragm, a rotatable driving shaft extending through the rear wall of the casing with its axis parallel to said stud shaft, a large gear mounted on the inner end of said driving shaft and engaging said pinion, said rear wall of the casing being thickened to form exterior and interior bosses affording long bearing surface for the drive shaft and for the rotor shaft.
8. In a horn of the class described, rear and front casings and a diaphragm clamped between them, in combination with means for vibrating the diaphragm, said means including a rotor, a driving pinion therefor, a stationary stud projecting endwise toward the diaphragm from the rear wall of the casing on the inner end of which said rotor and pinion are rotatably mounted, said stud extending through the rear wall of the casing and having screw connection therewith, accessible from the exterior of the casing for endwise adjustment of the rotor to and from the diaphragm, a rotatable driving shaft extending through the rear wall of the casing with its axis parallel to said stud shaft, a large gear mounted on the inner end of said driving shaft and engaging said pinion, said rear wall of the casing being thickened to form exterior and interior bosses affording long bearing surface for the drive shaft and for the rotor shaft and a strengthening and supporting rib extending between said bosses.
9. In a horn of the class described, rear and front casings and a diaphragm clamped between them, in combination with means for vibrating the diaphragm, said means including a rotor, a driving pinion therefor, a stationary stud projecting endwise toward the diaphragm from the rear wall of the casing on the inner end of which said rotor and pinion are rotatably mounted, said stud extending through the rear wall of the casing and having screw connection therewith, accessible from the exterior of the casing for endwise adjustment of the rotor to and from the diaphragm, a rotatable driving shaft extending through the rear wall of the casing with its axis parallel to said stud shaft, a large gear mounted on the inner end of said driving shaft and engaging said pinion, said parts being formed with an oiling system comprising a downwardly extending passage in the upper boss leading to the drive shaft intermediate its ends, a passage around the periphery of said shaft, a downwardly extending passage lengthwise through said rib leading from said peripheral passage to a passage around the periphery of said stud shaft and a longitudinal passage in the stud shaft leading from said peripheral passage lengthwise of the stud and opening through the bearing surface thereof in operative relation to the bearing surfaces of the pinion and rotor.
10. In a horn of the class described, rear and front casings and, clamped between them, a diaphragm having a suitable wear-piece, said rear casing consisting of a casting having its rear wall approximately parallel with and of approximately the same diameter as the unclamped portion of the diaphragm, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said driving shaft and engaging said pinion.
11. In a horn of the class described, rear and front casings and, clamped between them, a diaphragm having a suitable wear-piece, in combination with means for vibrat-

ing from said peripheral passage lengthwise of the stud and opening through the bearing surface thereof in operative relation to the bearing surfaces of the pinion and rotor.

10. In a horn of the class described, rear and front casings and a diaphragm clamped between them, in combination with means for vibrating the diaphragm, said means including a rotor, a driving pinion therefor, a stationary stud projecting endwise toward the diaphragm from the rear wall of the casing on the inner end of which said rotor and pinion are rotatably mounted, said stud extending through the rear wall of the casing and having screw connection therewith, accessible from the exterior of the casing for endwise adjustment of the rotor to and from the diaphragm, a rotatable driving shaft extending through the rear wall of the casing with its axis parallel to said stud shaft, a large gear mounted on the inner end of said driving shaft and engaging said pinion, said rear wall of the casing being thickened to form exterior and interior bosses affording long bearing surfaces for the drive shaft and for the rotor shaft and a strengthening and supporting rib extending between said bosses, said parts being formed with an oiling system comprising a downwardly extending passage in the upper boss leading to the drive shaft intermediate its ends, a passage around the periphery of said shaft, a downwardly extending passage lengthwise through said rib leading from said peripheral passage to a passage around the periphery of said stud shaft and a longitudinal passage in the stud shaft leading from said peripheral passage lengthwise of the stud and opening through the bearing surface thereof in operative relation to the bearing surfaces of the pinion and rotor.
11. In a horn of the class described, rear and front casings and, clamped between them, a diaphragm having a suitable wear-piece, said rear casing consisting of a casting having its rear wall approximately parallel with and of approximately the same diameter as the unclamped portion of the diaphragm, in combination with means for vibrating the diaphragm, said means including a rotor, a driving pinion therefor, a shaft on which said rotor and pinion are mounted, said rotor shaft being mounted in the rear wall of the casing and projecting endwise toward the diaphragm, a driving shaft extending through the rear wall of the casing with its axis parallel to said rotor shaft, a large gear mounted on the inner end of said driving shaft and engaging said pinion.
12. In a horn of the class described, rear and front casings and, clamped between them, a diaphragm having a suitable wear-piece, in combination with means for vibrat-
